UNITED STATES PATENT OFFICE.

JOSEPH J. RATHGEB, JR., OF NEW YORK, N. Y., ASSIGNOR TO RATHGEB GRATE COMPANY, INCORPORATED, OF NEW YORK, N. Y., A CORPORATION OF NEW YORK.

GRATE FOR BOILERS.

Application filed December 21, 1923. Serial No. 681,803.

My invention relates to steam or hot water boilers employing an induced or forced draft, the invention relating more specifically to the peculiar construction of grate 5 therefore comprising a plurality of hollow grate bars adapted to receive a circulation of water therethrough and of the general type and for the purposes now well known in the art.

The principal object of the invention is the production of a grate of the type above specified which shall be of simple construction and of ease of installation and which shall be so constructed as to permit a maximum of draft to be furnished to the fire so as to insure a complete combustion of the fuel at all places in the fire box.

Further advantages of the invention will be apparent from the accompanying description and consist, among others, in the novel means of interconnecting the separate grate bars, the particular construction of the grate bars whereby they may snugly and securely fit within the fire box and interfit with each other, means whereby the leakage of the draft is prevented endwise of the grate bars and means permitting the circulation of water through the grate bars in a direction whereby "thumping" or "pounding" is eliminated.

The invention consists in the novel grate construction and grate bars forming a part thereof hereinafter more particularly described and then specified in the claims.

In the accompanying drawings showing a practical embodiment of the invention:

Fig. 1 is a side elevation (partly broken away) of a boiler showing the invention as applied thereto.

Fig. 2 is a front elevation of the breeching.

Fig. 3 is a plan view of the grate per se showing it composed of a plurality of grate bars positioned longitudinally and in apposition to one another.

Fig. 4 is a side elevation of Fig. 3.

Fig. 5 is an enlarged front elevation of some of the grate units forming the grate.

Fig. 6 is a transverse section on the line 6—6 of Fig. 3.

Fig. 7 is a transverse section on the line 7—7 of Fig. 3.

Fig. 8 is a horizontal section on the line 8—8 of Fig. 4.

Fig. 9 is a transverse section on the line 9—9 of Fig. 3.

Fig. 10 is a fragmentary plan view of two of the grate units showing a modification.

Fig. 11 is a front elevation of Fig. 10.

Referring in detail to the several figures 60 of the drawings:

1 indicates the side wall of a boiler, 2 the front wall thereof, 3 the front and rear walls of the furnace each of which is provided with an opening having a channel 4 65 extending longitudinally of said walls. The inlet water pipe which is indicated at 5 connects with the grate units forming the grate and to be presently described. The outlet pipes from said grate units are indicated 70 at 6, the boiler tubes being indicated at 7.

Each individual grate unit comprises a hollow, metallic, elongated member substantially rectangular-shaped, the top of which is flat and is indicated at 8 and which is connected to the base 9 by the side walls 10, the end walls being indicated at 11. Secured to or cast integral with either end of the base 9 is a lug 12 adapted to interfit with the channels 4 in the front and rear walls 3 80 of the furnace whereby the grate units are held from endwise movement in said furnace. One end of each grate unit is reduced to form a shouldered portion 13 whereby a space of substantial width obtains intermediate the ends of the units when they are arranged in parallelism and in apposition to each other within the furnace to form the complete grate, the lugs 12 engaging within the channels 4 as has 90 been explained. (See Figs. 3 and 4.)

The grate units are connected together at their shouldered ends by nipples 14 screwed or otherwise inserted in suitable openings in the side walls of the units as shown in 95 Fig. 3. The inlet pipe 5 is connected to the ends of the two central units by a two-way pipe 15 so that water flowing through said pipe 5 will circulate through the units in the direction of the arrows and will finally flow 100 through the opposite ends of the two outside units and through the outlet pipes 6 which are connected thereto. I have found in practice that this construction is superior to those that have preceded it for the reason 105 that the cold water from the pipe 5 enters the units at or adjacent the central portion of the grate where the fire is apt to be hottest and where the cooling effect is most desired to prevent burning out of the units, the 110

water, which is progressively becoming more heated, leaving the grate at the extreme sides thereof where the fire is not nearly as hot and where the cooling effect of the water is not as necessary as at the center of the grate. This construction, furthermore, is desirable for the reason that the flow of water from the inlet pipe is a continuous one through one grate unit to and through the next succeeding grate unit and finally through the outlet pipe in contradistinction to some previous constructions in which the water flows simultaneously from a common inlet pipe or manifold through separate grate units to a common outlet pipe or manifold. In the latter construction the temperature of the several streams of the water after they leave the several units varies considerably with the result that their meeting in the outlet pipe or manifold produces "pounding" or "thumping" which is objectionable.

The sides of the grate units at the central portion thereof taper downwardly as indicated at 16, these tapered walls being connected to the straight side walls 10 by transverse walls 17. The top edges of said tapered sides are serrated as indicated at 18. When therefore, the units are arranged in juxtaposition longitudinally of each other within the furnace the tapered side walls 16 and transverse walls 17 form air chambers (see Fig. 6) and the serrated edges 18 form tortuous air slots so that the draft of air which may be forced into the ash pit of the furnace flows through the air chambers, through the tortuous slots and to the fire on the grate units in the combustion chamber.

To prevent any of the air from leaking or flowing from the air chambers through the spaces intermediate the walls of the grate units adjacent their ends so that it will all flow through the tortuous air slots described,

I have provided the sides of the units with semi-circular depressions 19 each adapted to register with a similar depression in the side of the next succeeding unit, whereby annular openings are formed each receiving a pin or plug 20 which may also be utilized as a spacing member whereby the proper space between the units is obtained.

In the modification illustrated in Figs. 10 and 11 the shouldered portions 13 are provided with a top wall or cover 21 which if so desired may be an integral part of each grate unit. The function of the top walls is to prevent ashes or clinkers from dropping down upon the pipe nipples to prevent them from being burnt out, and to prevent dust and dirt from accumulating in the spaces between the ends of the grate bars.

What I claim as my invention is:—

1. In a grate construction, a plurality of hollow grate bars arranged in parallelism longitudinally of each other and provided with reduced ends forming shouldered portions, nipples within the spaces formed by said shouldered portions connecting said bars together and plates covering said spaces and nipples.

2. In a grate construction, a plurality of hollow grate bars arranged in apposition to each other with spaces therebetween forming air slots, the side walls of said bars being formed with rounded depressions therein each adapted to register with the depression in the wall of the next succeeding bar to form round openings and plugs entering said openings and interfitting therewith for closing the ends of said air slots and for spacing said bars the proper distance apart.

Signed at New York in the county of New York and State of New York this 20th day of December, A. D. 1923.

JOSEPH J. RATHGEB, JR.
